COMBINED CLOCK, NIGHT LIGHT AND THERMOMETER

Charles O. Ising, Fort Smith, Ark.

Application March 14, 1955, Serial No. 35,029

Term of patent 14 years

(Cl. D42—7)

Fig. 1

Fig. 2

Figure 1 is a front elevational view of a combined clock, night light and thermometer embodying my new design; and

Figure 2 is a side elevational view of the same.

I claim:

The ornamental design for a combined clock, night light and thermometer, substantially as shown.
